THREAD CUTTER BLADE

**Fredric E. Douglas, Hopedale, Mass., assignor to
Draper Corporation, Hopedale, Mass., a corporation of Maine**

Application May 14, 1936, Serial No. 79,754

5 Claims. (Cl. 139—303)

The present invention relates to temple thread cutting mechanisms for looms, and has more particular reference to improvements in movable thread cutter blades therefor.

5 Thread cutting mechanisms of the type mentioned include a stationary ledger blade carried by the loom temple and a rocking and sliding cutter blade mounted in a guideway in the temple for cooperation with the ledger blade. It has 10 been proposed heretofore to make the movable cutter blade of a body portion, which may be of cast or forged metal and therefore quite substantial, with a separate steel cutting tip secured to the body portion by one or more fastening devices such as rivets, the steel tip being relatively hard and susceptible of taking a sharp cutting edge. The construction is such that operation of the mechanism causes a considerable rearward pull on the cutting tip.

20 Cutter blades constructed as just described have proven satisfactory in most respects, except that the rearward pull on the cutting tip imposes so much strain on the rivets that the latter soon loosen and wear, thus rendering the cutter 25 blade unserviceable. A number of attempts to prevent this have been made.

An object of the present invention accordingly is to provide an improved construction, whereby the above-mentioned difficulties will be overcome. 30 In accordance with this object, one feature of the invention resides in a thread cutting temple provided with a cutter blade having a rigid metallic body portion which is provided with a depending heel at its forward end and an upright 35 shoulder, a separate cutting tip secured to the body portion, and means for securing said tip to said body portion, said tip having an integral portion folded laterally in front of said shoulder and in contact therewith and rearwardly in contact with a side face of the body, thereby relieving the securing means of the strain of a longitudinal pull on said tip. As illustrated, the cutting tip is folded laterally in a U-shape to conform to the shape of the shoulder formed on the 40 body portion. This U-shaped portion is in contact with the shoulder and the pull of the cutting tip during the thread cutting operation is exerted upon the shoulder and not upon the fastenings securing the tip to the body portion.

45 50 With the above and other objects and features in view the invention will be described in connection with the accompanying drawing and pointed out in the appended claims.

In the drawing,

55 Figure 1 is a view in elevation of the rear face

of a temple embodying one form of thread cutting mechanism.

Figure 2 is a view in cross-section taken along the line 2—2 of Figure 1.

Figure 3 is a top plan view of the movable cutter blade shown in Figure 1.

Figure 4 is a view in side elevation of the cutter blade shown in Figure 3.

Figure 5 is a top plan view of another type of cutter blade, embodying my invention, and

10 Figure 6 is a view in side elevation of the cutter blade shown in Figure 5.

The temple illustrated in Figure 1 is provided with a supporting bar 8; a head carrying a pod 10, a cap 12 and a roll or rolls 14; a depending heel 16 by which the temple may be reciprocated; and a thread cutting mechanism which will later be described in detail.

The pod 10 and the cap 12 are provided with cooperating cut out portions constituting a guideway 18 which extends longitudinally and preferably entirely through the temple head. The guideway 18 is positioned in a substantially vertical plane and the side walls of the guideway extend in substantially parallel planes between 25 which the thread cutting mechanism is positioned and guided.

The thread cutting mechanism illustrated in Figures 1 to 4, inclusive, comprises a flat steel ledger blade 20 and a movable cutter blade 22. 20 The ledger blade 20 is positioned vertically in the guideway 18 at one side of the rearward end thereof and extends upwardly into a groove or slot in the temple head where it is secured by the head of a screw 24. The rear vertical corner 30 of the ledger blade 20 is sharpened to form a cutting edge.

The movable cutter member 22 is formed with a rigid metal body portion 26 which is preferably flat on both sides to fit into and to be positioned 40 in a vertical plane in guideway 18. The forward end of the body portion 26 is of usual form having a depending operating member 28 which is adapted to be struck by the lay (not shown) for causing the blade 22 first to rock, to hook behind 45 the filling and then to slide forwardly past the cutting edge of the ledger blade 20. The blade 22 is returned to its normal position by conventional form of the spring 30.

The rearward end of the body portion of the 50 blade 22 is provided with a rearwardly extending finger 32 to which a cutting tip 34 is secured by rivets 35 and which forms a backing for the cutting tip 34. The cutting tip 34 is formed of a flat resilient piece of steel as will later be de- 55

scribed. The body portion 26, the operating member 28 and the backing finger 32 are preferably cast integrally of brass or cast iron, but they may be otherwise constructed from strong and rigid material if so desired.

The mechanism disclosed above is substantially the same as that described and claimed in United States Letters Patent Number 1,919,146, granted July 18, 1933, on an application filed in my name, 10 to which reference may be had for a more detailed description.

Referring now particularly to Figures 2, 3 and 4, it will be noted that the backing finger 32 is provided at its forward end with a rounded abutment or shoulder 36 formed by cutting a transverse slot in the body portion 26. The cutting tip 34 is of a flat piece of steel which is bent transversely in the form of a U. The U-portion fits against the shoulder 36 and prevents relative 20 movement between the cutting tip 34 and the finger 32 when the movable cutter member 22 is moved forwardly to sever a filling thread. It is apparent that this construction prevents a rearward pull on the rivets during the cutting operation, and, consequently, these rivets do not readily loosen and wear. In other words, the pull of the cutting operation is exerted upon the shoulder or abutment 36 and not upon the rivets.

As shown in Figure 3, the cutting tip 34 extends 30 rearwardly along the backing finger 32. The rearward end of the tip 34 is provided with a depending cutting portion having a sharpened edge 38 which cooperates with the ledger blade 20. The rearward end of the tip 34, as shown in Figures 1, 2 and 3 is bent slightly away from the backing finger 32 which insures that the cutting tip 34 will at all times cooperate with the ledger blade 20. The temple is provided with means for adjusting the relative lateral positions of the 40 movable cutter blade 22 and the ledger blade 20. As shown in Figure 1, a resilient metal strip 40 is positioned in the guideway 18 on the side opposite to the ledger blade 20. An adjusting screw 42 bears against the lower end of the strip 40 45 and by turning the adjusting screw 42 the strip 40 is bent, which moves the movable cutter blade 22 toward the ledger blade 20.

In Figures 5 and 6 there is disclosed another form of cutting blade embodying my invention. 50 In this modification, the movable cutting blade 44 having a depending operating member 46 is arranged to be struck by the lay for causing the blade 44 first to rock the rearward end of the blade downwardly and then to slide the blade forwardly to sever a filling thread. After the severing operation is completed, the blade 44 may be returned to its initial position by a spring of any usual type. The cutting blade 44 is provided with a rearwardly extending portion 50. The portion 60 50 is provided with a rounded upwardly extending abutment or shoulder 52 the purpose of which will later be disclosed.

As shown in Figure 5, a flat resilient piece of steel is folded upon itself to form a U-shaped cutting tip 54. This U-shaped cutting tip 54 is arranged to fit against the shoulder 52 and the cutting tip 54 is rigidly secured to the movable cutting blade by a plurality of rivets 55. As in the form shown in Figures 1 to 4, inclusive, there is no 70 rearward pull on the rivets 55, or other fastenings used, during the cutting or severing operation, the pull being exerted on the shoulder 52.

The cutting tip 54 is provided with a pair of cutting members 56, 58 which are each provided 75 with cutting edges 60. These cutting edges are

parallel to each other and lie in substantially the same plane. As shown in Figure 5, the movable cutter blade 44 extends only to about the mid portion of the cutting tip 54, and does not back up the entire length of the cutting tip 54. The cutting members 56, 58 are bent toward each other as shown in Figure 5. A stationary cutter (not shown) of any usual type is secured to the temple and is inserted between the cutting tips and operates with the cutting edges 60 to sever a filling 10 thread.

Reviewing briefly, the embodiment of the invention shown in Figures 1 to 4, inclusive, discloses a cutting tip 34 which is secured to the movable cutter blade 22 by rivets or other fastenings and 15 because of the U-shaped portion of the cutting tip 34 any pull on the cutting tip is exerted upon the shoulder or abutment 36 and not upon the rivets. In the same manner, in the type of cutting tip 54 shown in Figures 5 and 6, the rearward pull of the 20 cutting tip 54 is exerted upon the shoulder 52 and not upon the rivets securing the tip 54 to the movable cutting blade 44.

Having thus described the preferred embodiments of my invention, I claim:

25

1. As an article of manufacture, a cutter blade for thread cutting temples; said blade having a rigid metallic body portion, said body having a depending heel at its forward end and an upright shoulder forwardly of its rearward end, a separate 30 steel cutting tip, and a fastening device securing said tip to one side face of said body portion, said tip having an integral portion folded laterally in front of said shoulder in contact therewith and rearwardly in contact with a side face 35 of the body to relieve said fastening device of the strain of a longitudinal pull on said tip.

2. As an article of manufacture, a cutter blade for thread cutting temples; said blade having an elongated rigid metal body portion, said body being provided with a depending heel at its forward end and a shoulder intermediate its ends, said shoulder having a substantially vertical forward edge, a separate flat steel cutting tip, and a fastening device securing said tip to one side face of 40 said body portion rearwardly of said shoulder, the forward end of said tip being folded about said edge in contact therewith and rearwardly in contact with a side face of the body to relieve said fastening device of the strain of a rearward pull 50 on said cutting tip.

3. As an article of manufacture, a cutter blade for thread cutting temples; said blade having an elongated rigid metal body portion, said body being provided with a depending heel at its forward 55 end and a shoulder intermediate its ends, said shoulder having a substantially vertical forward edge, a separate steel cutting tip folded about said edge of said shoulder to provide parallel integrally joined portions in contact with opposite 60 side faces of said body portion, and a fastening device securing both of said portions of said tip to said body portion at a point rearwardly of said edge.

4. As an article of manufacture, a cutter blade 65 for thread cutting temples; said blade having an elongated rigid metal body portion, said body being provided with a depending heel at its forward end and a shoulder intermediate its ends, said shoulder having a substantially vertical forward 70 edge, a separate flat steel cutting tip comprising parallel side portions in contact with opposite faces of said body portion, said side portions being joined at their forward ends by an integral connecting portion which engages about said edge, at 75

least one of said side portions having at its rearward end a downwardly extending cutting edge, and a rivet securing said side portions to said body portion at a point rearwardly of said edge.

5. As an article of manufacture, a cutter blade for thread cutting temples; said blade being comprised of a rigid metallic body portion having at its forward end a depending heel and at its rearward end a rearwardly extending backing finger, 10 said body portion having a slot extending downwardly from its upper edge at a point forwardly of said finger, a resilient steel cutting tip having

parallel flat portions in contact with opposite side faces of said body portion, said flat portions being connected at their forward ends by an integral connecting portion which is positioned in said slot in contact with the rearward edge thereof, one of 5 said flat portions having at its rearward end a downwardly extending cutting edge which is spaced slightly away from the rearward end of said backing finger, and a rivet securing said flat portions of said tip to said body portion at a point 10 between said slot and said finger.
